United States Patent Office

Des. 185,997

Patented Aug. 25, 1959

185,997

CAMERA STAND OR SIMILAR ARTICLE

Joseph R. Lusby, Kansas City, Mo.

Application January 2, 1958, Serial No. 49,108

Term of patent 14 years

(Cl. D61—1)

Fig. 1 is a front perspective view of a camera stand or similar article, showing my new design;

Fig. 2 is a rear perspective view; and

Fig. 3 is a top plan view thereof.

I claim:

The ornamental design for a camera stand or similar article, as shown.
